UMBRELLA, PARASOL, SUNSHADE, AND THE LIKE

Filed April 7, 1926

Inventor
Annie E. Bagshaw
by B. Singer, A.M.

UNITED STATES PATENT OFFICE.

ANNIE ELIZABETH BAGSHAW, OF HAMPSTEAD, LONDON, ENGLAND.

UMBRELLA, PARASOL, SUNSHADE, AND THE LIKE.

Application filed April 7, 1926, Serial No. 100,893, and in Great Britain June 6, 1925.

This invention relates to umbrellas, parasols, sunshades and the like of the type having a removable cover, with a central aperture adapted to be secured around the stick adjacent the top notch by suitable detachable means and to be secured to the ends of the ribs at its circumferential edge by detachable caps or other suitable devices carried thereby and attachable to the ribs.

According to the present invention a sleeve fitting is provided formed with or having attached thereto the top notch, which sleeve is adapted to be fitted to the stick or handle by screw means. Another part preferably forming or attached to the tip or ferrule is also adapted to be fitted to the stick or handle, or the said sleeve fitting, by screw means. The sleeve, and the other part in screwed relation therewith or with the stick, form a clamp adapted to grip and retain the cover between them. The cover at the central aperture is preferably bound and reinforced by a wire ring, thread or the like and secured in an annular groove on a ring or bound by an eyelet of any desired form, the central aperture in any case being large enough to pass over the end of the stick or sleeve as the case may be to come adjacent the top notch.

And in order that the invention may be better understood, it will now be described with reference to the accompanying drawings in which:

The figure of drawing is a sectional view of the same showing some of the ribs complete and also showing the caps by which the cover is connected to the outer ends of the ribs.

The stick 8 has a reduced upper portion 20 which fits into a tube or sleeve 21 to which it is attached by cement, glue or otherwise. This sleeve 21 is screw threaded on the exterior and the construction is equivalent to screw threading the end of the stick, with the exception that the sleeve 21 will give greater service. The sleeve 5 and top notch 6 are screw threaded on the interior screw on to this screw threaded end to the stick, but this screw threaded end projects some distance through the sleeve. 23 is a ring of metal or other suitable material having a clearance aperture to pass over the screw threaded end of the stick. The ring 23 on the exterior has a cir-

cumferential groove in which the apertured part of the cover 12 is bound by thread or the like. This ring 23 rests on the top of the top notch 6 and is clamped in position 55 by the cap or ferrule 10 which screws on to the projecting end of the stick. To prevent the runner 24 of the umbrella from being pushed too far up the stick when the umbrella is opened the usual fixed pin or stop provided for the purpose is replaced by a springy movable stop 25. This resembles the usual stop such as 26 for holding the runner 24 in position, but the stop 25 is inverted. The advantage of this construction is that 60 the stop 25 can be pressed inwards when the stick has to be removed from the runner, which would not be possible if the usual fixed stop above referred to were employed.

As the angular position of the stick with 70 regard to the runner 24 may vary when different covers are in position, the runner is formed with a number of openings or slots 27 any one of which can engage the usual movable catch at the other end of the handle 75 (not shown on the drawing) for holding the parts of the umbrella in the closed position.

The cover 12 is provided with the requisite number of caps or the like 17, in the form of sockets to fit on the ends of the ribs. These 80 caps are preferably sewn or otherwise fixed to the cover at the end of the seams between the panels. On the inside the seams in desired positions may be provided with loops 18 of cotton, wire or the like if desired, which 85 are attachable to hooks 19 fixed to the ribs and serve for maintaining the cover in correct position on the frame.

What I claim and desire to secure by Letters Patent of the United States of America 90 is:

In an umbrella of the type comprising a detachable cover, a stick having a reduced end, a metal sleeve fitting around the reduced end and attached thereto and provided 95 with an exterior screw thread, an internally threaded sleeve adapted to screw on to said exterior screw threaded sleeve so that the said externally threaded sleeve projects therethrough and provided with a top notch, 100 a plurality of ribs pivotally carried by the top notch, a cover with a central reinforced

aperture, adapted to come on the top notch centrally with respect to the axis of the stick, a plurality of caps carried by the cover for engagement with the ends of the ribs, a tip 5 having an internal screw thread engaging the portion of the externally threaded sleeve which projects through the top notch, the

annular surface of the tip being adapted to come on the outer portion of the central reinforcement of the cover and clamp it between the top notch and the tip. 10

In witness whereof I affix my signature.

ANNIE ELIZABETH BAGSHAW.
